UNITED STATES PATENT OFFICE.

DAVID SMOUSE, CHARLES W. SMOUSE, AND DAVID H. SMOUSE, OF MOUNT PLEASANT, IOWA.

SUGAR-EVAPORATOR.

SPECIFICATION forming part of Letters Patent No. 272,093, dated February 13, 1883.

Application filed November 24, 1882. (No model.)

To all whom it may concern:

Be it known that we, DAVID SMOUSE, CHARLES W. SMOUSE, and DAVID H. SMOUSE, of Mount Pleasant, in the county of Henry and State of Iowa, have invented certain new and useful Improvements in Sugar-Evaporators; and we do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 represents a perspective view, looking from above down on the device. Fig. 2 is a similar view of the cover. Fig. 3 is an enlarged face and side view of a detail, showing the connection between the pan and finisher. Fig. 4 is a sectional detail view, showing the construction of the "kinks." Fig. 5 is a side elevation of one of the receiving-pipes.

This invention relates to improvements in evaporators, more especially to those used for sugars and sirups.

The object of the invention is to produce an evaporator which shall be self-skimming, and in which the sirup will be thoroughly strained and "finished."

The invention consists in a combined evaporating-pan and finisher having the peculiarities of construction hereinafter set forth.

In the annexed drawings, the letter A represents the evaporator, consisting of a pan, B, and finisher C, made separate and united together at their ends, as shown at a, by the connector I. As indicated, the evaporator is made preferably rectangular, and its corners are strengthened by the exterior angle-plates or corner-irons, a'. The pan B is formed with an extension, b, at one side, out of line with the finisher C, as shown. In this extension the pan is furnished with the three walls b' b² b³, the first about on the line of the edge of the finisher, the three forming a receptacle, b⁴, in which is a hole, b⁵. The ends of this extension b, outside of the walls b' b², are formed into offsets D and D', in which are inclined boards or plates, preferably perforated, d d', loosely connected to the tops of the walls b' b², and extending out into said offsets. At the op-

posite side of the pan, in its angles, are placed the corners E, made angular at the back, so as to fit the angles of the pan, and rounded in front. These corners or blocks E have flanges 55 e at the bottom, forming a recess, e', beneath, and have passages e², which lead through the corners from the top down to the recess. Fitting in said holes are the turned-up ends f of the supply or receiving pipes F, which terminate at their ends f' in the pan.

Seated within the pan is the cover G, resting against the wall b' at one side and the edge of the pan at the other, and leaving a space at each end in the pan, outside of the cover, as t 5 shown. This cover G is lined with metal, and consists of a top, g, side pieces, g' g', and sliding jackets g² g², having handles, as shown. The side pieces, g' g', are provided with grooves g⁴ g⁴, in which the ends of the jackets fit, and 70 said pieces g' g' extend beyond these grooves, the ends at one side resting against the corners E E and holding the cover in position.

Extending from the pan B, underneath the cover, is the educt-pipe H, which passes into 75 the connector I and leads from the pan to the finisher. This connector consists of two plates of metal, h h, which are placed on the inner sides of the ends of the pans B C, and they all are bolted together, as indicated in Fig. 3. 80 Through the registering-holes h' in these the educt-pipe H, passes, and is provided with the cut-off h².

Arranged across the bottom of the pan B and finisher C are several lowridges or kinks, 85 K, which divide them into several compartments and strengthen the bottom. These kinks are made by placing strips of metal k' from side to side of the evaporator and then turning the metal bottom L over the upper edge 90 90 and two sides of the strips and bolting them together, all as shown at l l in detail in Fig. 4.

At one side of the evaporator is placed the tank M, for receiving the juice before it comes to the pan. This tank has a pair of grooves, 95 m m, on each side, in which are to be fitted the ends of screens or filters N N, thus dividing the tank into two compartments, m' m², the latter having a faucet, m³. One filter only is employed in use, and, when it is clogged another is placed in the adjoining set of grooves and the other filter removed and cleaned.

Only one tank is shown in the drawings, but two are to be employed, one at each end of the pan; or one large tank may be used with two sets of screens, forming three compartments, the middle to receive the crude sirup, the other two to discharge it into the pan.

This evaporator is placed, as usual, upon the brick arch or frame-work, so as to be heated, the offset *b* being to one side of the brick-work, 10 and not having any fire under it. The crude juice is poured into the compartment *m'* of the tank *M*, and, passing through the screen or filter *N* into compartment *m''*, is drawn off through the faucet *m³*, and passes down the pipe *E* into the pan *C*. As the juice is discharged at *D D'*, 15 it flows under the jackets *g² g²*, beneath the cover *g*, and by aid of the interior heat and sliding jackets *g² g²* a double automatic current is formed, and the screen is carried to *D* and 20 *D'*, and the pure defecated juice flows through the pipe *H* into the finisher *C*. As the scum, &c., rises within the pan beneath the cover, it is forced by the current into the offsets *D D'*, and, passing over and up the inclines *d d'*, falls 25 into the receptacle *b⁴*, and is drawn off through the hole *b⁵*. The pure juice flows through the educt-pipe *H* into the first division of the finisher, and passes over the first ridge into the next division, and so on until it passes into the 30 last and is drawn off at *p* a finished sirup. The pan, as thus constructed, has a double capacity, and the juice being admitted at both ends increases the working facility. The cover having two jackets, the juice passes in at both ends 35 and runs rapidly under the influence of the heat beneath, and the metal lining keeps the heat in, being practically air-tight.

As thus constructed, the device is adapted to work automatically. The juice in the pan 40 is separated from the scum, the latter being forced to the offsets and the defecated juice passes from under the cover into the finisher. This makes the evaporator self-skimming, and attention in this regard is only needed to remove the buckets as often as they become filled 45 with the discharged scum. The juice is thoroughly defecated, and under the cover is sub-

jected to an intense heat, which purifies it, and the purer portion passes off below through the educt-pipe into the finisher. Herein it is still 50 operated upon, and is graduated off until it comes out at *p* a finished article.

Having thus described our invention, what we claim is—

1. An evaporator having the offsets *D D'*, inclines *d d'*, and scum-receptacle *b⁴*, as set forth. 55

2. The evaporator having the corner, *E*, with passage *e'*, and the pipe *F*, having the end *f* in said passage, as set forth.

3. An evaporator having the cover *G* placed 60 in the middle and a space for receiving the juice at each end, as set forth.

4. The cover *G*, having sides *g' g'*, with grooves *g⁴ g⁴*, and the sliding jackets *g² g²*, fitting said grooves, as set forth. 65

5. The cover *G*, having the sliding jackets *g² g²*, whereby is formed a double current, as set forth.

6. The cover *G*, having a metallining, as set forth. 70

7. The pan *B*, finisher *C*, and educt-pipe *H*, in combination with the connector *I* and the cover *G*, the pipe *H* leading from under the cover into the finisher *C*, as set forth.

8. The connector *I* and pans *B C*, secured 75 together, in combination with the educt-pipe *H*, having the cut-off *h*, and the cover *G*, the pipe *H* leading from under the cover into the pan *C*, as set forth.

9. The juice-tank *M* having the filters *N N*, 80 as set forth.

10. The evaporator, having the metal corner irons, as set forth.

11. The strips *k*, in combination with the continuous bottom *L*, turned over them, as set forth. 85

In testimony that we claim the foregoing as our own invention we all affix our signatures in presence of two witnesses.
